(57) **CLAIM**

The ornamental design for a seat for carrying a person, as shown and described.

DESCRIPTION

FIG. 1 is a front perspective view of a first embodiment of a seat for carrying a person showing my new design; FIG. 2 is a front view of the seat for carrying a person shown in FIG. 1;

FIG. 3 is a rear view of the seat for carrying a person shown in FIG. 1;

FIG. 4 is a rear perspective view of the seat for carrying a person shown in FIG. 1;

FIG. 5 is a left-side view of the seat for carrying a person shown in FIG. 1;

FIG. 6 is a right-side view of the seat for carrying a person shown in FIG. 1;

FIG. 7 is a top view of the seat for carrying a person shown in FIG. 1;

FIG. 8 is a bottom view of the seat for carrying a person shown in FIG. 1;

FIG. 9 is a perspective view of the seat for carrying a person shown in FIG. 1, illustrating the seat for carrying a person in another configuration;

FIG. 10 is a perspective view of the seat for carrying a person shown in FIG. 1, illustrating the seat for carrying a person in another configuration;

FIG. 11 is a front perspective view of a second embodiment of a seat for carrying a person showing my new design;

FIG. 12 is a front view of the seat for carrying a person shown in FIG. 11;

FIG. 13 is a rear view of the seat for carrying a person shown in FIG. 11;

FIG. 14 is a rear perspective view of the seat for carrying a person shown in FIG. 11;

FIG. 15 is a left-side view of the seat for carrying a person shown in FIG. 11;

FIG. 16 is a right-side view of the seat for carrying a person shown in FIG. 11;

(Continued)

FIG. 17 is a top view of the seat for carrying a person shown in FIG. 11;

FIG. 18 is a bottom view of the seat for carrying a person shown in FIG. 11;

FIG. 19 is a perspective view of the seat for carrying a person shown in FIG. 11, illustrating the seat for carrying a person in another configuration; and,

FIG. 20 is a perspective view of the seat for carrying a person shown in FIG. 11, illustrating the seat for carrying a person in another configuration.
